UNITED STATES PATENT OFFICE.

GODFREY STIBBE, OF LEICESTER, ENGLAND.

KNITTED GLOVE AND METHOD OF PRODUCING THE SAME.

1,346,516.

Specification of Letters Patent. Patented July 13, 1920.

Application filed August 8, 1916. Serial No. 113,728.

To all whom it may concern:

Be it known that I, GODFREY STIBBE, subject of the King of Great Britain, residing at Leicester, in the county of Leicester, England, have invented certain new and useful Improvements in or Relating to Knitted Gloves and Methods of Producing the Same, of which the following is a specification, reference being had therein to the accompanying drawing.

This invention relates to knitted gloves and to the method of producing the same and has for its object to produce an improved machine made glove one of the advantages of the process forming the invention being that articles of the character concerned can be made much quicker and cheaper than heretofore.

By the process of manufacture herein to be described, the main portions of the glove *i. e.* wrist, hand, thumb and fingers may be made on the same machine, thus obviating the customary pressing-off and running on operations.

In carrying out the process, a circular knitting machine is employed for preference, although it may be possible to make use of the same method on a flat knitting frame or straight bar machine.

A machine knitted glove according to this invention comprises a seamless wrist and hand, a thumb and a series of fingers knitted in the flat and with selvaged edges as a jointless continuation of the hand.

The essence of the invention is the formation of the finger portions as jointless continuations or extensions of the hand portion, *i. e.* without a seam or joint at the base or root of the fingers where the circular fabric is merged into the separated finger portions.

In the improved glove the two outside fingers may be seamed down the inner side only and the two inside fingers seamed down each side.

In a modified form of the glove all the fingers may be seamed down each side; further, in such glove the fingers may be formed with seamless extremities.

The thumb of the improved glove may be finished with a single seam, or it may have seams upon two opposite sides in which latter case it may also have a seamless extremity.

It is also a feature of the invention that in a glove characterized by the aforesaid

features, the aggregate loops in the courses of the combined fingers is greater than the number of loops in the courses of the hand portion.

In describing the invention reference will be made to the accompanying drawings wherein:

Figure 1 is a flat view of the complete glove formed according to this invention.

Fig. 2 is a perspective view of the same.

Fig. 3 is a perspective view showing an alternative form of the improved glove.

Fig. 4 is a perspective diagrammatical view of a blank partly formed and showing the thumb portion.

Fig. 5 is a similar view showing a further stage in the process the blank having the finger portions formed thereon.

Fig. 6 is a further similar view showing a blank having finger portions formed according to an alternative method.

Fig. 7 shows the blank of Fig. 6 carried a stage further in the process.

Fig. 8 is a diagram of the needle circle and is hereinafter referred to in explaining the method of obtaining a greater number of loops in the courses of the combined fingers than there are in the courses of the hand portion of the glove.

Fig. 9 illustrates a detail in the finish of the finger extremities.

Figs. 4, 5, 6, 7 and 9 are drawn to a smaller scale than Figs. 1, 2, 3 and 8, and throughout the drawings like parts are designated by the same reference characters.

The improved glove shown in Figs. 1 and 2 has a wrist and hand portion 1 of circular fabric seamlessly combined with a thumb 2 and fingers 3, 4, 5 and 6, the outside fingers 3 and 6 being seamed at 7 down the inner side only and the two inside fingers 4, 5 being seamed at 8 down each side.

The glove shown in Fig. 3 has a wrist and hand portion 1 of circular fabric seamlessly combined with thumb and fingers 100 similarly to the glove shown in Fig. 1, except that in this alternative form all the fingers are seamed at 9 down each side and at the extremities 10 are without seams.

The thumb 2 may have a seam 11 down each side as shown in Figs. 2 and 3, or it may, as will be hereinafter described, be formed with a single seam. When seamed upon two sides it may be without a seam at the tip 12 as shown in Fig. 3, or the extrem- 110

ity may be closed in the manner shown in Fig. 2.

- The method — subject to modifications hereinafter mentioned — consists in first 5 knitting a piece of circular fabric to form the wrist and part of the hand portion 1. (Fig. 4) up to the root of the thumb, after which knitting proceeds upon a certain number of the needles while the others remain 10 out of action, the length of fabric formed by the said needles which continue in action constituting what may be termed the thumb fabric 2^a. The number of needles which continue in action to form the said thumb fabric 15 will, of course, depend upon the desired width and length of such fabric.
- After the formation of the thumb fabric 2^a knitting again proceeds upon all the needles 20 and circular fabric is produced to complete the hand portion 1 of the glove up to the base or root of the fingers. The length of thumb fabric 2^a is now found to be seamlessly united at each end with the 25 fabric 1 constituting the hand portion. After completing the hand portion, knitting is continued upon certain individual sets of the needles to produce lengths of fabric 3^a, 4^a, 4^b, 5^a, 5^b and 6^a; (Fig. 5) to 30 constitute finger fabrics. For instance, certain needles may continue in action while the others are inactive, the operating needles producing the fabric portion 3^a or 6^a to form one of the outside fingers, *i. e.* either the first or fourth finger of the glove. The fabrics 3^a and 6^a may be made at different times or both at the same time, the 35 needles producing same going out of action when the parts are finished, after which certain other needles come into action and knit a length of fabric to constitute one half of the next finger, *i. e.* either the inside 4^a, 5^a or outside 4^b, 5^b, of the second or 40 third fingers, this process being repeated to 45 separately produce the said lengths of fabric to constitute the requisite half portions for the second and third fingers, it being arranged that the inside halves 4^a, 5^a and outside halves 4^b, 5^b of the said second and 50 third fingers shall be appropriately positioned upon opposite sides of the circular hand fabric 1 to come together and have their respective edges 4^c, 4^d and 5^c, 5^d joined to 55 form the complete fingers.
- In an article or blank thus produced (Fig. 5) the thumb fabric 2^a and the finger fabrics 3^a, 4^a, 4^b, 5^a, 5^b, 6^a, are seamlessly united with the main fabric 1, each separately formed length has a selvage at each 60 edge, the thumb, first finger and fourth finger are formed whole the second and third fingers are formed in halves. Briefly stated therefore the process may be said to consist in forming on the same machine a circular 65 wrist and hand portion having integral

therewith a whole thumb fabric, whole outside finger fabrics, and half inside finger fabrics.

To obtain the necessary width of fabric for the fingers, the finger fabrics or lengths may be formed in such a manner that they overlap one another at the base as shown in Fig. 5 and thus provide the additional material necessary at the base or root to form a gusset between the fingers. 7

This overlapping may be effected by employing for the knitting of a finger portion some of the needles upon which the previous or adjacent finger portion was or is to be formed; thus by using some needles twice for producing adjacent finger fabrics the number of loops in the circular course or courses of the glove in the region of the roots of the fingers can be made to exceed the maximum number of needles in the machine and consequently exceed also the maximum number of loops in the circular courses of the hand portion of the glove so that the additional material requisite for the fingers is provided. This will be here- 90 inafter fully explained.

The process already described, may admit of variation as regards the formation of the finger portions, that is to say, it may be immaterial as to whether one finger portion is formed before another or whether the said finger fabrics shall be formed at different times or two or more of them at the same time. Obviously it may be an advantage to proceed with the finger formation in a circular order commencing say with the finger fabric 3^a for the first finger, then forming the fabric 4^a for the inside half of the second finger, next the fabric 5^a for the inside half of the third finger, then 10 the fabric 6^a for the fourth finger followed by the fabric 5^b for the outside half of the third finger, and lastly the fabric 4^b for the outside half of the second finger. Or this order might be reversed. Or again finger 110 fabrics may be formed simultaneously upon opposite sides of the circular hand portion. For example, the first and fourth finger fabrics 3^a and 6^a may be formed at the same time as also may be the separate 115 halves 4^a, 4^b of the second finger and the halves 5^a, 5^b of third finger; or the front half of one, *e. g.* 4^a and the back half 5^b of the other of these fingers may be formed and then the halves 5^a and 4^b. 120

To facilitate the clear comprehension of the improved process, a specific example of the production of a glove blank upon a circular knitting machine, the cylinder of which is equipped with 160 needles, will 125 now be described, it being understood that the numbers of needles referred to are not binding but are given merely as an illustration.

The glove is commenced by knitting upon 130

the full complement of needles a length of circular fabric.

The thumb fabric is knitted upon 58 needles while the rest remain quiescent. 5 Then the circular knitting is continued on all needles. The finger fabrics are next knitted each upon a separate group of needles which for purpose of description will be designated (a), (b), and so on and 10 are illustrated in Fig. 8. The various groups will be referred to in circular order around the circle of needles the finger fabrics concerned being shown in Fig. 5. The first finger fabric is formed upon a group 15 of needles *a* comprising 46 in number. The front half of the second finger (fabric 4^a) is formed upon a group *b* of needles 26 in number and of which 6 belong to group *a*. The front half of the third finger (fabric 5^a) is made upon a group of 20 needles *c* 22 in number and of which 6 belong to group *b*. The needles (42 in number) of the next group *d* produce the fourth finger fabric 6^a. The back half of the third finger (fabric 5^b) is made upon a group *e* 25 composed of 22 needles 6 of which belong to group *d*, and the back half of the second finger (fabric 4^b) is made upon a group *f* composed of 26 needles 6 of which belong 30 to group *e*. Thus while there are but 160 needles in the cylinder, 184 loops are formed in the circumference of the glove by reason of the overlapping or double use of some of the needles as shown at the points *g*, *h*, *i*, *j*. 35 Conveniently the groups may operate simultaneously in pairs thus *a* and *d*, *b* and *e*, and *c* and *f*, or they may operate individually. It is an important advantage in connection with the method involved in this invention that the edges of the thumb and finger 40 fabrics are selvaged as this greatly facilitates the joining up of such parts and enables a neater seam to be formed than is possible when the edges are raw besides obviating the possibility of fraying or running back.

In finishing the glove the first and fourth fingers are completed by seaming together the edges 3^b, 3^c and 6^b 6^c of the finger fabrics, the second and third fingers are completed by bringing together the half finger portions on opposite sides of the glove and joining them down each side. The lengths 50 of fabric for the first and fourth fingers are preferably so disposed on the hand portion, that when they are folded or doubled lengthwise and seamed the seamed edge will be situated upon the inside of the fingers, *i. e.* between such fingers and the next thereby 55 making such fingers and the entire glove 60 seamless on the outside.

According to the modified method illustrated in Figs. 6 and 7 the hand portion 1 and the thumb fabric 2^a are made in the manner 65 already described but the finger portions are

made in a continuous manner from one side only of the tubular hand portion 1.

The finger portions may extend from the front or back of the hand portion but preferably they are integrally united with the back 70 as shown in Fig. 6 and comprise a length of fabric 13 for the first finger, a piece 14 for the second finger a piece 15 for the third finger and a piece 16 for the fourth finger. These finger fabrics are made twice the 75 length of the fingers and are knitted in extension from the hand portion in the manner already described as regards the overlapping parts at the base of the fingers.

In completing the glove according to this 80 method, the finger fabrics—each cut or made in the proper length—are doubled or folded over in the manner shown in Fig. 7, their ends are joined to the edge 17 of the opposite side of the hand portion 1, and then 85 the opposing halves of each doubled or folded finger portion are joined together down the sides as shown at 9 in Fig. 3. This method produces fingers which are seamless 90 at the extremity 10 seeing that the fold 10^a (Fig. 7) in each continuous finger portion ultimately forms the tip.

By forming the finger extensions on the back part of the hand portion the join of 95 the ends of such finger portions to the hand part will be situated on the inside of the glove at the locality 17^a (Fig. 7) and will therefore be less conspicuous.

In joining the turned over ends of the finger portions to the edge 17 of the hand 100 portion the said ends may slightly overlap one another as shown in Fig. 7 to give the desired fullness at the base of the fingers, and the joining up may be effected by linking or seaming the parts together or in any 105 other convenient manner.

To obviate a square formation at the tips of the fingers formed by the fold 10^a in the finger portions, the sides of the latter may be trimmed off near the folded part (as indicated by the dotted lines in Fig. 9) before 110 or after the edges have been seamed or otherwise joined together.

Instead of making all the fingers by the method illustrated in Figs. 6 and 7 some of them, *e. g.* the outside fingers 3 and 6 may be made in the manner described with reference to Figs. 2 and 5.

The thumb admits of being completed in several ways. For instance the side edges of 120 the loop of fabric 2^a may be joined in which case a thumb of the kind shown in Fig. 3 is produced the tip 12 being seamless. The folded part 12^a of the fabric 2^a which forms the seamless tip may be trimmed in the manner previously described with reference to Fig. 9 to avoid a square end. Another method is to cut the loop 2^a through at the fold 12^a and after shaping the opposing 125 halves join them together along their edges. 130

- This makes a thumb of the kind shown in Fig. 2. A further method is to make the thumb fabric extra wide and sever the inner end of the loop at the point 2^b from the hand portion 1 thus producing a thumb fabric of the same character as the finger fabrics 3^a and 6^a (Fig. 5). The thumb is completed by joining together the longitudinal side edges, closing the tip or end and securing the said edges at the base to the part of the hand portion from which the loop termination was severed. A thumb thus produced will have a single seam situated down the inside.
15. The improved glove may or may not be provided with a rib top, *i. e.* a ribbed wrist portion (not shown) but when it is to have this the said ribbed portion may be run on in the usual manner.
20. What I claim then is:—
1. As a new article of manufacture, a machine knitted glove comprising a seamless tubular hand, an integral thumb, a series of fingers knitted in the flat and with selvaged edges as jointless continuations of the tubular hand, the aggregate loops in the courses of the combined fingers being greater than the number of loops in the courses of the hand, substantially as described.
  2. As a new article of manufacture, a machine knitted glove comprising a seamless tubular hand, an integral thumb, a series of fingers knitted in the flat and with selvaged edges as jointless continuations of the tubular hand, the aggregate loops in the courses of the combined fingers being greater than the number of loops in the courses of the hand, a seam down the inner side only of the two outside fingers and a seam down each side of the two inside fingers.
  3. As a new article of manufacture, a machine knitted glove comprising a seamless tubular hand, an integral thumb, a series of fingers knitted in the flat and with selvaged edges, as jointless continuations of the tubular hand, the aggregate loops in the courses of the combined fingers being greater than the number of loops in the courses of the hand, and the thumb being seamed upon two opposite sides.
  4. As a new article of manufacture, a machine knitted glove, comprising a seamless tubular hand, an integral thumb, a series of fingers knitted in the flat and with sel-

vaged edges as jointless continuations of the tubular hand, the aggregate loops in the courses of the combined fingers being greater than the number of loops in the courses of the hand, and the thumb being seamed upon two opposite sides and at the extremity.

5. The method of producing a knitted glove of the kind herein described which consists in knitting a circular fabric to form part of the hand, then knitting upon a portion only of the needles to form a thumb fabric then resuming on all the needles to complete the hand, then knitting upon certain individual groups of the needles to produce separate lengths of flat fabric for the fingers, some of the needles of one group being used in the next group of needles whereby the adjacent finger fabrics produced by such groups of needles overlap one another and the aggregate loops in the courses of the combined fingers is made to exceed the number of loops in the courses of the circular hand fabric.

6. The method of producing a knitted glove of the kind herein described which consists in knitting a circular fabric to form part of the hand, then knitting upon a portion only of the needles to form a thumb fabric, then resuming the knitting on all the needles to complete the hand, then knitting upon certain individual groups of the needles to produce separate lengths of flat fabrics for the fingers, some of the needles of one group being used in the next group of needles whereby the adjacent finger fabrics produced by such groups of needles overlap one another and the aggregate loops in the courses of the combined fingers is made to exceed the number of loops in the courses of the circular hand fabric, the fabrics for the two outside fingers being formed whole and the fabrics for the two inside fingers being each formed in separate halves upon opposite sides of the circular hand fabric, and finally seaming up the thumb and fingers to complete the glove, substantially as described.

In testimony whereof I affix my signature in presence of two witnesses.

GODFREY STIBBE.
